RACK FOR HOLDING SUGAR PACKETS

Kenneth W. Bromley, Hobart, Ind., assignor, by mesne assignments, to Harold Leonard & Co., Inc., New York, N.Y., a corporation of New York

Filed Aug. 30, 1963, Ser. No. 76,408

Term of patent 14 years

(Cl. D44—24)

FIG. 1

FIG. 2FIG. 3FIG. 1 is a front perspective view of a rack for holding sugar packets;

FIG. 2 is a side elevational view thereof; and

FIG. 3 is an end elevational view thereof.

I claim:

The ornamental design for a rack for holding sugar packets, substantially as shown.
